(57) **CLAIM**

The ornamental design for a light switch, as shown and described.

DESCRIPTION

FIG. 1 is a perspective view of a light switch showing the design according to a first embodiment;

FIG. 2 is a top plan view thereof;

FIG. 3 is a first side view thereof;

FIG. 4 is a second side view thereof, opposite the view of FIG. 3;

FIG. 5 is a third side view thereof;

FIG. 6 is a bottom plan view thereof, opposite the view of FIG. 2;

FIG. 7 is a fourth side view thereof, opposite the view of FIG. 5;

FIG. 8 is a perspective view of a light switch showing the design according to a second embodiment;

FIG. 9 is a top plan view thereof;

FIG. 10 is a first side view thereof;

FIG. 11 is a second side view thereof, opposite the view of FIG. 10;

FIG. 12 is a third side view thereof;

FIG. 13 is a bottom plan view thereof, opposite the view of FIG. 9; and,

FIG. 14 is a fourth side view thereof, opposite the view of FIG. 12.

The broken lines appearing in various views are for illustrative purposes only and form no part of the claimed design. The dot-dash-dot broken lines appearing on the bottom plan views represent boundaries of the claimed design and form no part of the claimed design.
